UNITED STATES PATENT OFFICE.

FRANCIS KARR, OF HOLLAND, MICHIGAN.

BED-SPRING.

1,388,263.

Specification of Letters Patent. Patented Aug. 23, 1921.

Application filed August 5, 1918, Serial No. 248,459. Renewed February 4, 1921. Serial No. 442,596.

To all whom it may concern:

Be it known that I, FRANCIS KARR, a citizen of the United States, residing at Holland, in the county of Ottawa and State of Michigan, have invented certain new and useful Improvements in Bed-Springs, of which the following is a specification.

My invention relates to improvements in bed springs, and its objects are: first, to dispense with the use of "tie rods" such as are used in ordinary spiral spring bed bottom construction; second, to provide a means whereby the greatest flexibility between coils is attained with the least complication of construction; third, to provide a means whereby the surface coils in spiral spring bed construction may be interwoven and interlocked to form a closely linked, very strong and flexible surface, and, fourth, to provide a means whereby the weight of the spring structure will be reduced to the minimum while the flexibility and strength of the structure will be raised to the maximum.

I attain these objects by the construction shown in the accompanying drawing, in which Figure 1 is a plan of a surface coil with the connecting elements of adjacent coils shown. Figs. 2 and 3 are modified forms of connecting elements showing the preferable forms of construction between adjacent surface coils in the border rows of the structure, and, Fig. 4 is a plan of the surface coils in the makeup of the border rows, and of one coil as used in the surface within the border rows, that is, throughout the interior or non-border rows.

Similar reference characters indicate similar parts throughout the several views.

In the construction of this spring it is desirable to provide a different connecting construction for the border and the body of the spring surface, as indicated in Fig. 4, in which 1 indicates a body spring surface coil, 1' indicates the plain border coils and 1'' indicates a corner spring coil. The corner coil should be made with a connecting hook 3' and a connecting crimp 2'' so arranged that the connecting hook of one coil will be made to engage with, and freely clamp around the crimp on the adjacent coil, as shown at the relatively upper side, and the relatively right hand side of the coil 1''. The free end of this coil is carried around and knotted to the coil wire, as at b. The

plain border coils are, also, provided with 55 the connecting hook 3' and the connecting crimp 2'', or other like device for pivotally connecting these coils, but the free ends of these coils are projected outwardly and have hooks 4 formed so they may be made to engage the rings or loops 4 on adjacent coils.

The body, or inner, coils of the surface construction in the assembled springs are provided with two horizontal rings, 3, adjacent to each other, a vertically disposed 65 ring 2 at one side, and a hook 4 at the end of the coil wire. The vertically disposed rings 2 are left open at a, a, sufficiently to allow the adjacent horizontally disposed ring 3 to be readily passed through to form the 70 connections shown in Fig. 1, and the hook 4 is left open at c so it may be readily hooked into one of the horizontally disposed rings 3, as shown, after which the end c is to be formed around the wire forming a 75 closely fitting, but free moving link connection. By this means, it is plain to see, the spring surface will not only be made more lasting and strong than with the usual tie rod construction, but will be much more 80 yielding and flexible in all directions, so far as vertical movement is concerned.

It is not necessary that the crimp formation shown at 2'' be used in this construction, as the offset form shown at 2' is equally efficient and much more easily formed, and several other forms of connection may be used, but I prefer the crimp and hook as shown in Figs. 2 and 4.

When assembling the center coils, either 90 with the border coils, or with the other center coils, the horizontally disposed rings are passed over the end of the hooks 4 and along the coil to the point a where they are made to enter the vertically disposed ring, as 95 shown, and as hereinbefore described.

What I claim as new in the art, is:

1. In spiral spring bed bottom and cushion construction, border surface coils flexibly interlinked, and central coils interlinked 100 with the border coils and with each other by means of horizontally disposed eyes engaged with vertically disposed eyes forming a strong, light, flexible surface construction.

2. In spring bed bottom and cushion 105 construction, surface coils having eyes or rings horizontally disposed on two sides and vertically disposed on two sides of each surface

coil all so arranged that the horizontal rings on one surface coil may be interlinked with the vertical rings on adjacent surface coils throughout the surface construction of the 5 springs.

3. In spring bed bottom construction, a border row of coils having integral pivotal connecting elements radiating from three sides thereof, corner coils having two integral pivotal connecting elements radiating at right angles, and body coils each having two integral horizontally disposed rings, and two integral vertically disposed rings all arranged so each coil may be pivotally 10 connected directly with all adjacent coils 15

to form a flexible surface construction for spiral spring bed bottoms.

4. In a spring bed bottom or the like, in combination, a series of wire rings normally lying in a common plane and each 20 comprising the terminal coil of a helical spring, each of the rings being provided with radially projecting eyes formed from the wire of which the ring is composed and the eyes of adjacent rings being inter- 25 engaged.

Signed at Grand Rapids, Michigan, July 18, 1918.

FRANCIS KARR.
